Primary Examiner — Keli L Hill(74) *Attorney, Agent, or Firm* — John H. Choi & Associates(57) **CLAIM**

The ornamental design for a multi-purpose grooming device, as shown and described.

DESCRIPTION

FIG. 1 is a perspective view of an embodiment of the multi-purpose grooming device showing my new design; FIG. 2 is a front plan view of the multi-purpose grooming device of FIG. 1;

FIG. 3 is a rear plan view of the multi-purpose grooming device of FIG. 1;

FIG. 4 is a left side view of the multi-purpose grooming device of FIG. 1, with the right side view being a mirror image of the left side view;

FIG. 5 is a top plan view of the multi-purpose grooming device of FIG. 1;

FIG. 6 is a bottom plan view of the multi-purpose grooming device of FIG. 1;

FIG. 7 is FIG. 2 with a front upper grip detailed;

FIG. 8 is an enlarged view of the front upper grip of FIG. 7;

FIG. 9 is FIG. 3 with a rear upper grip detailed;

FIG. 10 is an enlarged view of the rear upper grip of FIG. 9;

FIG. 11 is FIG. 4 with a left intermediate grip detailed, a right intermediate grip on the right side being a mirror image of the left intermediate grip; and,

FIG. 12 is an enlarged view of the left intermediate grip of FIG. 11.
